DESIGN FOR A COMPARTMENT CONTAINER FOR PERFUMES

Robert B. Karoff, New York, N. Y.

Application December 9, 1936, Serial No. 66,405

Term of patent 3½ years

To all whom it may concern:

Be it known that I, Robert B. Karoff, a citizen of the United States of America and resident of the city, county, and State of New York, have invented a new, original, and ornamental Design for a Compartment Container For Perfumes, of which the following is a specification, reference being had to the accompanying drawing, forming a part thereof.

In the drawing,

I claim:

The ornamental design for a compartment container for perfumes as shown.

ROBERT B. KAROFF.
